VESSEL-LEVELING DEVICE FOR GALLEY
RANGES

Robert E. Cooney, New Haven, Conn.

Application April 26, 1939, Serial No. 270,087

2 Claims. (Cl. 248—139)

This invention relates to apparatus for use in connection with galley ranges or cooking apparatus used upon shipboard, and more particularly to a device for holding cooking vessels in operative position with respect to the range or stove in such a manner that the vessel will at all times be held in a level position.

Ships and boats are normally provided with a stove or range of some character by which cooking may be performed upon the vessels. It is not practicable to seat a cooking vessel directly upon the upper surface of the stove or range, as may be done on land, as the movement of the boat is apt to dislodge the vessel or spill the contents thereof.

It is, therefore, desirable to arrange for the holding of the vessel in a suspended position above the stove, such that the vessel will depend freely from the support so that it may accommodate itself to the movement of the boat, and will always be maintained in a level position. Moreover, stoves or ranges used upon boats are of various sizes, and it is advantageous to provide a single support which may be adjustable to all sizes of such cooking devices, and at the same time be securable to all types of ranges or stoves, so that it may be used universally.

One object of the present invention is the provision of a vessel-leveling or supporting device for galley ranges, which is adapted to maintain the cooking utensil supported thereby in a level position at all times, regardless of the rocking of the boat.

Another object of the invention is the provision of a vessel-leveling or supporting device for galley ranges which is adapted to be secured to the usual range and is provided with means for freely suspending the cooking utensil so that it is capable of universal movement, or movement in any direction, whereby it will always be maintained at a level position.

A still further object of the invention is the provision of a vessel-leveling or supporting device for galley ranges such that the device may be readily attached to the usual range, and which may be adjusted to be applied to ranges of various sizes or widths.

A still further object of the invention is the provision of a vessel-leveling or supporting device of the character described, and an improved utensil hanger which may readily be secured to a vessel of any size, and which in turn is supported by means providing for its universal movement to compensate for changes in level of the boat.

To these and other ends the invention consists in the novel features and combinations of parts to be hereinafter described and claimed.

In the accompanying drawing:

- 5 Fig. 1 is a front elevational view of a vessel-supporting device embodying my invention;
- Fig. 2 is a sectional view through the extensible supporting rod of the apparatus on line 2—2 of Fig. 1;
- 10 Fig. 3 is a side elevational view of the end standards;
- Fig. 4 is a view of reduced size of the parts shown in Fig. 1 showing the operation of the device when in a tilted position;
- 15 Fig. 5 is a top plan view of the hanger employed with my device; and
- Fig. 6 is a view of the base of an end standard of slightly modified form for use with a guard rail of circular cross section.
- 20 To illustrate a preferred embodiment of my invention, I have shown in Fig. 1 the upper portion of a range or stove 10, which may be of any suitable character for use upon boats or similar vessels. Such ranges are usually provided with
- 25 a guard rail, shown at 11, which rail may be supported from the range by brackets 12. In the form shown, it will be understood that the guard rail 11 is comprised of side members or runs, as well as the front member, shown in the front view of Fig. 1.

The vessel-supporting attachment which is the subject matter of the present application is designed to be detachably secured to this rail, and more particularly to the side runs thereof. For this purpose the attachment consists of the end standards 13, which may be of similar form, and which are provided at their lower ends with inwardly facing channel or U-shaped portions 14 designed to embrace the side runs of the guard rail 11. These end standards 13 may be detachably secured to the rail by means of the thumb screws 15.

The front vertical edge portion of each of the standards 13 is provided with a series of recesses 45 or notches 16, these notches being defined by upwardly extending lips or hook-like members 17 which form abutments serving to prevent a rod or the like from being dislodged from the notch 16 after being placed therein. It will be understood that the two standards 13 will be provided with registering recesses 16 so that the recesses in one standard will lie opposite those in the other standard.

An extensible supporting member is provided to span the distance between the end supporting

standards and to be received and retained in the notches 16. This member comprises two telescoping sections 18 and 19, which, as shown, may be hollow, the section 19 being received in the section 18, and preferably making a close sliding fit therein. Adjacent the outer end of the section 18 a sleeve or collar 20 is secured therein, the projecting end of which is of smaller size than the section 18, and to this sleeve is secured a ring or handle 21 which will preferably be of some non-conducting material. It will be noted that the handle 21 is provided with a shoulder 22, which is spaced from the shoulder formed by the end of the section 18, so that the projecting end of the sleeve 20 may be received in the recess 16 of an end standard 13, with the standard being disposed between the shoulder 22 and the end of the section 18. This arrangement provides in effect a reduced portion on the supporting member to be received in the recess 16 in such a manner as to prevent longitudinal movement of the section 18 relatively to the end standard 13.

In a similar manner a sleeve 23 is inserted in the end of the section 19, to which sleeve is secured a handle 24 also of non-conducting material, this handle being provided with a shoulder 25, between which shoulder and the end of the section 19 the corresponding standard 13 is adapted to be embraced. It will be understood that when the extensible member comprising the sections 18 and 19 is removed from the end standards 13, as may freely be done by giving this member a slight upward and outward movement so as to withdraw it from the recesses 16, the member may be extended or contracted to the desired length to fit the width of the range or stove with which it is to be used.

Slidably mounted upon this extensible member is a supporting hook comprising a body portion 26 and a hook portion 27. The body portion 26 will be arranged to embrace the extensible member to hold the supporting hook thereon. Preferably there will be a relatively close fit between the body portion 26 and the extensible member, so that, while this member may be moved along the extensible member as desired, it will ordinarily maintain its position thereon. The hook portion 27 is of the usual form, so that a ring-shaped object may be supported thereby and be free to swing in a universal movement.

In order to support a cooking vessel or utensil from the hook 27, I have provided a hanger of special form, shown more particularly in Figs. 1 and 5. This hanger is provided at its upper portion with a ring 28 formed by twisting the material of which the hanger is formed into ring formation. Below the ring the arms of the hanger extend in a substantially horizontal direction, as shown at 29 and 30, and are provided with bifurcated ends 31 and 32, which depend downwardly and are prevented from spreading apart by means of straps 33. Upon the lower ends of the bifurcated arms 31 and 32 are provided hooks 34, which, as shown in Fig. 1, are designed to engage below the rim 35 of a cooking utensil 36.

It will be understood that when the hanger is not in use, the spring tension of the material of which it is made will normally cause the arms 31 to approach the arms 32, or, as viewed in Fig. 1, the hooks 34 upon one side of the device will approach the hooks 34 on the other side. When it is desired to secure the hanger

to a vessel, the user may grasp the straps 33 and pull the arms apart until they are spread sufficiently to receive the rim 35 of the vessel 36 therebetween. The straps 33 are then released, and it will be seen that the hanger will grip the ring of the vessel at four points, this grip being increased due to the weight of the vessel when the hanger is supported by the ring 28. When it is desired to detach the hanger from the vessel, it is merely necessary to grasp the straps 33 and pull outwardly on these straps to disengage the hooks 34 from the rim 35.

In Fig. 6 of the drawing I have shown a somewhat modified form of end standards 13, which are designed for gripping a circular guard rail. In this instance the lower portion of the standard 13a is of V-shaped form, as shown at 37, so as to embrace the circular rail 38. Below the V-shaped portion the foot of the end standards is of L-shaped form, as shown at 39, and a set screw 40 is arranged to bear against the lower side of the rail 38 so as to force it into the V-shaped socket 37.

It will be seen that I have provided an attachment for galley ranges which is adjustable to any size of range, and which may readily be attached to the guard rail of the range so that the extensible supporting member may be positioned at any desired vertical height above the top of the range. The cooking utensil, while suspended above the range, will be suspended in close proximity to the flame, and will be practically as efficient as if the utensil were seated on the range itself. Moreover, the cooking utensil is suspended in a convenient and efficient manner, and moreover is suspended for universal movement, so it will always be held in a level position regardless of the level of the range itself. The extensible member comprising the sections 18 and 19 will be securely held against any sliding movement longitudinally in the end standards 13, and at the same time when it is removed from these standards it may be readily adjusted to any desired length.

While I have shown and described some preferred embodiments of my invention, it will be understood that it is not to be limited to all of the details shown, but is capable of modification and variation within the spirit of the invention and within the scope of the appended claims.

What I claim is:

1. An attachment for a galley range having a rail, comprising a pair of standards detachably securable to said rail, each of said standards being provided with a series of recesses opening through the front edge thereof, an extensible supporting member having its ends seated in said recesses to be supported by said standards, a supporting hook slidably supported by said member, a hanger freely suspended from said hook and designed to be secured to a vessel to be supported by the attachment, said hanger comprising a pair of resilient oppositely disposed bifurcated arms, and said arms having means at their ends to grip a vessel whereby a four-point contact with the vessel is provided.

2. An attachment for a galley range having a rail, comprising a pair of standards detachably securable to said rail, each of said standards being provided with a series of recesses opening through the front edge thereof, an extensible supporting member having its ends seated in said recesses to be supported by said standards, a supporting hook slidably supported by said

member, a hanger freely suspended from said hook and designed to be secured to a vessel to be supported by the attachment, said hanger comprising a member having an eye to be engaged with said hook, and oppositely disposed arms projecting outwardly and downwardly from said eye, the outer ends of said arms being

bifurcated and spread apart to provide a four-point contact with a cooking utensil, said arms being resilient whereby the hooks upon one arm are normally urged in a direction toward the hooks of the other arm.
